UNITED STATES PATENT OFFICE

PAUL MOHRMANN, OF CHICAGO, ILLINOIS, ASSIGNOR TO FRIEDELEY-VOSHARDT COMPANY, OF CHICAGO, ILLINOIS, A CORPORATION OF ILLINOIS.

DESIGN FOR A PLATE FOR DROP-LIGHT FIXTURES.

46,686.

Specification for Design.

Patented Nov. 24, 1914.

Application filed August 20, 1914. Serial No. 857,781. Term of patent 3½ years.

To all whom it may concern:

Be it known that I PAUL MOHRMANN, a citizen of the United States, residing at Chicago, in the county of Cook and State of Illinois, have invented a new, original, and ornamental Design for a Plate for Drop-Light Fixtures, of which the following is a specification, reference being had to the accompanying drawings, forming a part thereof.

In the drawings:—Figure 1 is a bottom plan view of a plate embodying this design. Fig. 2 is a side elevation of the same.

Copies of this patent may be obtained for five cents each, by addressing the "Commissioner of Patents, Washington, D. C."

I claim:

The ornamental design for a plate for drop light fixtures, as shown.

In testimony whereof I have hereunto set my hand at Chicago, Illinois, this 17 day of August, 1914.

PAUL MOHRMANN.
